Sydney I. Prescott ATTORNEY

UNITED STATES PATENT OFFICE.

SYDNEY I. PRESCOTT, OF NEW YORK, N. Y., AND FRANCIS J. RUMMLER, OF LYNDHURST, NEW JERSEY.

WHEEL.

Application filed February 24, 1922. Serial No. 538,867.

To all whom it may concern:

Be it known that we, SYDNEY I. PRESCOTT and FRANCIS J. RUMMLER, citizens of the United States, respectively, residing in the city, county, and State of New York, and the town of Lyndhurst, county of Bergen, and State of New Jersey, have invented a new and useful Improvement in Wheels, of which the following is a specification.

10 This invention relates to an invention in wheels, particularly of the type disclosed in our co-pending application, filed February 13, 1922, Serial No. 536043, and the main object of the invention is the production of a wheel having improved means for firmly seating a demountable rim on the wheel body and whereby certain stresses developed in road use are more evenly distributed in that part of the wheel body 20 which directly receives road shocks. With this and other objects not specifically mentioned in view, the invention consists in certain constructions which will be herein-after fully described and then specifically 25 set forth in the claims hereunto appended.

In the accompanying drawing, which forms a part of this specification and in which like characters of reference indicate the same or like parts, the figure is a cross-sectional view of a wheel constructed in accordance with the invention, the body and wheel holding devices being omitted.

In carrying the invention into effect, there is provided a wheel body and rim, one 35 of which is provided with a surface engaging the other, which surface has the contour of the periphery of a spheroidal frustum or is otherwise transversely curved. In the best constructions, the body and the rim 40 have contacting surfaces each of which has the contour of the periphery of a spheroidal frustum, and the center of this spheroidal frustum lies at the intersection of the wheel axis and the plane of the inboard edges of 45 said surfaces; "inboard," as herein used, meaning toward the center of the vehicle on which the wheel is used. The exact position of this center, however, may be varied in certain constructions within the invention.

50 Referring to the drawing, which illustrates only one of a number of possible concrete embodiments of the invention, 1 is the disc body provided with an integral broad

rim supporting seat 2 having the contour 55 of the periphery of a spheroidal frustum the center of which lies at the intersection of the wheel axis, indicated in the drawing by the line W—A, and the plane of the inboard edges of said seat, which plane is indicated by the line P—IE. The line R in the drawing indicates the radius of the sphere of which the spheroidal frustum is a part. Adjacent its inboard edge, the seat 2 is reversely bent at 3 to stiffen the structure.

Engaging the seat 2 is a rim provided with a seat-engaging surface 4 having the contour of the periphery of a spheroidal frustum and reversely bent at 5, so that the 70 contacting surfaces of the body and the rim have the contour of the periphery of a spheroidal frustum reversely bent adjacent their inboard edges, the center of this frustum lying at the intersection of the wheel 75 axis and the plane of the inboard edges of said surfaces.

The construction above described provides separable body and rim elements having broad engaging surfaces which more 80 efficiently distribute the stresses developed, prevent the two elements from being jammed together tight enough to prevent easy separation, and provide for efficient seating notwithstanding the tolerances required in manufacture.

Changes and variations within the scope of the claims may be made in the structure by means of which the invention is carried into effect. The invention therefore is not 90 to be restricted to the precise details of the structure shown and described.

What is claimed is:

1. A wheel comprising a body and a rim the contacting surfaces of which have the 95 contour of the periphery of a spheroidal frustum the center of which lies in the wheel axis inboard from the rim seat.

2. A wheel comprising a body and a rim the contacting surfaces of which have the 100 contour of the periphery of a spheroidal frustum and are reversely bent adjacent their inboard edges, the center of said frustum lying in the wheel axis inboard from the rim seat.

3. A wheel comprising a body and a rim the contacting surfaces of which have the contour of the periphery of a spheroidal

frustum the center of which lies at the intersection of the wheel axis and the plane of the inboard edges of said surfaces.

4. A wheel comprising a body provided with a rim supporting seat having the contour of the periphery of a spheroidal frustum the center of which lies in the wheel axis inboard from the rim seat, and a rim engaging said seat.
5. A wheel comprising a disc body provided with an integral broad rim supporting seat having the contour of the periphery of a spheroidal frustum the center of which lies in the wheel axis inboard from the rim seat, and a rim engaging said seat.
6. A wheel comprising a body provided with a rim supporting seat, and a rim provided with a seat engaging surface having the contour of the periphery of a spheroidal frustum the center of which lies in the wheel axis inboard from the rim seat.
7. A wheel comprising a body and a rim the contacting surfaces of which are transversely curved approximately about a center lying in the wheel axis inboard from the rim seat.

In testimony whereof, we have signed our names to this specification.

SYDNEY I. PRESCOTT.
FRANCIS J. RUMMLER.
